UNITED STATES PATENT OFFICE

156,563

TIE RACK

Harry D. Sallee, New York, N. Y.

Application May 7, 1948, Serial No. 146,219

Term of patent 14 years

(Cl. D33—8)

To all whom it may concern:

Be it known that I, Harry D. Sallee, a citizen of the United States, and a resident of New York city, in the county of Bronx and State of New York, have invented a new, original, and ornamental Design for a Tie Rack, of which the following is a specification, reference being had to the accompanying drawings, forming part thereof.

In the drawings:

Fig. 1 is a face view of a tie rack, embodying my new design.

Fig. 2 is a top plan view thereof.

Fig. 3 is an end view.

I claim:

The ornamental design for a tie rack, substantially as shown.

HARRY D. SALLEE.
